UNITED STATES PATENT OFFICE.

JOSEPH P. DUCKETT, OF SISTERS, OREGON.

GRATE FOR BURNING SAWDUST.

Application filed March 22, 1924. Serial No. 701,103.

To all whom it may concern:

Be it known that I, JOSEPH P. DUCKETT, a citizen of the United States, residing at Sisters, in the county of Deschutes and State of Oregon, have invented a new and useful Improvement in Grates for Burning Sawdust, of which the following is a specification, reference being had to the accompanying drawings.

10 My invention relates to incinerating devices as a class.

The object of my invention is to provide a device of this class, adapted to burn sawdust, and particularly in large quantities, 15 as for example in the refuse thereof from mills which manufacture wood products. Also to provide in my device a series of 20 pyramidal arranged grates having a large central air area, with lateral outlets and dampers to close the same, operable singly or together, as well as an ash grate with damper to close the openings therein. These 25 objects, as well as other advantages, I attain by the construction, combination and arrangement of parts illustrated in the accompanying drawings which form a part thereof.

Fig. I is a sectional elevation of an ash-pit and my device assembled thereon in operative position, partly in section on the line 30 I—I in Fig. II.

Fig. II is a top plan view, with parts in section, on the line II—II in Fig. I.

Fig. III is a plan view of the ash-grate 35 damper.

Fig. IV is a plan view of a damper ring for an incinerating grate.

Fig. V is a sectional view of said damper ring on the line V—V in Fig. IV.

40 Fig. VI is a detail, perspective view of one of the supporting pedestals for an incinerating grate.

Fig. VII is a detail, perspective view of a supporting bracket for ash grate damper ring.

Like characters refer to like parts in the views.

The device is arranged in and upon an ash-pit 1, of common type, having a doorway 2. Cross-beams 3 are supported at three ends on the ash-pit, the fourth end being supported on a lateral beam 4, over the doorway. A series or ring-shaped grates are arranged pyramidal. The lowest grate 5 has a horizontal base 6, with a vertical ring 7 extending upwardly from the inner periph-

ery of the base. Along the upper part of the ring 7 is a series of lateral openings 8. In the base 6 is a series of vertical openings 9. The grate 5 is supported by its base on the beams 3 and 4. A ring-formed horizontal damper 10 has openings 10, in it positioned to register with the openings 9, which damper is arranged to open and close the openings 9, and mechanism 11 is provided to operate this damper. A ring-formed, vertical damper 12 is arranged below and in vertical parallel plane with the inner surface of the grate ring 7, so that when raised it will slide over the ring surface and close the openings 8. Lever mechanism 13 is provided and arranged in connection with the damper 12 to raise it over the openings 8 to close them and lower it from them for opening to draft. The next superimposed grate 14 is of similar construction to that of the grate 5, except that it does not have the openings 9 of the latter. The grate 14 is supported on top of the grate 5 and also by pedestals 15, the feet of which rest upon the beams 3. The bottom of this grate extends a convenient distance over the top of the grate 5. The next superimposed grate 16 is of similar construction to that of the grate 14 and is supported upon the latter and upon pedestals 17. A cover 18 is superimposed upon and extends over the grate 16. The grates 14 and 16 have lateral openings similar to those in the grate 5, also similar vertical dampers to 90 open and close these draft openings, and damper mechanism of like character to raise and lower the dampers, all as illustrated. The damper mechanism may be arranged to operate for raising and lowering the dampers singly or simultaneously as desired. The damper mechanism may be arranged to 95 operate for raising and lowering the dampers singly or simultaneously as desired. The position of saw-dust material 19, to be incinerated, is indicated in Fig. I. The interior area above the central part of the ash-pit, and within the respective grate rings, 100 is open to allow complete upward draft through the same and laterally through the grate opening. A wall 21 is shown in part. This is intended to indicate the wall of any arched oven structure of common type which 105 may be erected over the grates.

It will now be observed that when saw-dust material 19 is deposited from any convenient source within the arched walls mentioned, and upon the grates arranged within such walls, the dampers are operated to open part or all of the damper openings, as may

be desired, to obtain the most effective draft to insure combustion of the saw-dust, which, from its fine nature tends to pack and obstruct ready combustion. It will be seen that a strong lateral draft from the center can thus be produced through the material at varying heights thereof. This insures a very steady and complete combustion. It will further be seen that the grates, each 10 extending over the one below, tends to prevent the material from packing closely in vertical position against the vertical grate surface, and leaves a space in the angle thus formed, into and through which the air may 15 more readily pass. The object of the damper openings 10' is to provide means to allow ashes to drop or be raked through them into the ash-pit below, from which they may be removed more easily. I am aware that various 20 devices have been made to burn material which may pack more or less in mass, but none is arranged or constructed as mine is. It should be remembered that the object of my device is to cause a steady combustion 25 of all the material and in the least period of time. It is well known that a very large amount of saw-dust accumulates about a mill handling wood products, which occupies needed space and also creates a dangerous 30 fire risk to the mill. It is highly advantageous to quickly and economically dispose of this waste material. At the same time, also to derive benefit and profit from its incineration in any possible manner. The arrangement 35 of the grates is such that the heat derived from combustion of material thereon may be employed to develop power. This would necessarily require an enclosing wall. If it is desired simply to dispose of the saw- 40 dust, the incinerator may be placed conveniently to the mill to receive the saw-dust and the mass incinerated very rapidly and effectually. The pedestals afford an additional support for the grates, tending to retain 45 them in position and prevent their warping because of the intense heat.

I claim—

1. In an incinerating device, the combination of illustrated elements as follows; a 50 series of ring-shaped grates pyramidal arranged and superimposed, each grate having lateral draft openings in its upper vertical part, the grates above the lowest extending over the one below a convenient distance, and circular dampers arranged within each 55 grate ring, vertically slidable over its inner surface and adapted to open and close the draft openings.

2. In an incinerating device, the combination of illustrated elements as follows; a series of ring-shaped grates pyramidal arranged and superimposed, each grate having lateral draft openings in its upper vertical part, the grates above the lowest extending over the one below a convenient distance,

circular dampers arranged within each grate ring, vertically slidable over its inner surface and adapted to open and close the draft openings, and damper mechanism arranged within the grate areas, connected with the 70 dampers and adapted to operate them singly or together.

3. In an incinerating device, the combination of illustrated elements as follows; a series of ring-shaped grates pyramidal arranged and superimposed, each grate having lateral draft openings in its upper vertical part, the grates above the lowest extending over the one below a convenient distance, a 75 cover, supported over the uppermost of the grate series, and extending likewise over the grate below, and circular dampers arranged within each grate ring, vertically slidable over its inner surface and adapted to open and close the draft openings.

4. In an incinerating device, the combination of illustrated elements as follows; a series of ring-shaped grates pyramidal arranged and superimposed, each grate having lateral draft openings in its upper vertical part, the grates above the lowest extending over the one below a convenient distance, a cover, supported over the uppermost of the grate series, and extending likewise over the grate below, circular dampers arranged within each grate ring, vertically slidable over its inner surface and adapted to open and close the draft openings, and damper mechanism arranged within the 80 grate areas, connected with the dampers and 85 adapted to operate them singly or together.

5. In an incinerating device, the combination of illustrated elements as follows; a ring-shaped grate having lateral draft openings and a supporting base with vertical 90 openings in said base, arranged for the passage of material through them, a series of similar grates pyramidal superimposed above the said lowest grate, the base of each 95 grate extending a convenient distance over the one below, a cover, supported over the uppermost of the grate series, and likewise extending over the grate below, and auxiliary supporting means arranged within the 100 grate area to support each grate between the 105 said lowest grate and the grate cover.

6. In an incinerating device, the combination of illustrated elements as follows; a ring-shaped grate having lateral draft openings and a supporting base, a series of similar 110 grates pyramidal superimposed above the said lowest grate, the base of each grate extending a convenient distance over the one 115 below, a cover, supported over the uppermost of the grate series, and likewise extending over the grate below, auxiliary supporting means arranged within the grate area to support each grate between the said lowest 120 grate and the grate cover, circular dampers arranged within each grate ring, vertically 125

- slidable over their respective inner surfaces and adapted to open and close the draft openings of each grate, and damper mechanism arranged within the grate areas, connected with the dampers and arranged to operate them singly or together.
7. In an incinerating device, the combination of illustrated elements as follows; a ring-shaped grate having lateral draft openings and a supporting base with vertical openings in said base, arranged for the passage of material through them, a series of similar grates pyramidal superimposed above the said lowest grate, the base of each grate extending a convenient distance over the one below, a cover, supported over the uppermost of the grate series, and likewise extending over the grate below, auxiliary supporting means arranged within the grate area to support each grate between the said lowest grate and the grate cover. 35 40
- 10 15 20 25 30 35 40 45 50 55
8. In an incinerating device, the combination of illustrated elements as follows; an ash-pit, a ring-shaped grate having lateral draft openings and a supporting base resting on the ash-pit, a series of similar grates pyramidal superimposed above the said lowest grate, the base of each grate extending a convenient distance over the one below, a cover, supported over the uppermost of the grate series, and likewise extending over the grate below, and auxiliary supporting means arranged within the grate area to support each grate between the said lowest grate and the grate cover.
9. In an incinerating device, the combination of illustrated elements as follows; a ring-shaped grate having lateral draft openings in its upper vertical part, and a circular damper arranged within the grate ring, vertically slidably over its inner surface and adapted to open and close the draft openings.
10. In an incinerating device, the combination of illustrated elements as follows; a ring-shaped grate having lateral draft openings in its upper vertical part, a circular damper arranged within the grate ring, vertically slidably over its inner surface and adapted to open and close the draft openings, and damper mechanism within and below the grate area, connected with the damper and adapted to operate it.
